DRESS

Henry J. Pearl, Los Angeles, Calif., assignor of
one-half to Harvey L. Barker, Los Angeles,
Calif.

Application May 20, 1942, Serial No. 443,675

4 Claims. (Cl. 2—74)

The invention relates to a dress and particularly to an arrangement for simplifying the problem of raising or lowering the waist line of a one-piece dress or uniform.

With regard to whether a one-piece dress is provided with a removable belt or a set-in belt, generally speaking heretofore there have been two methods of forming the waist line of a one-piece dress. If the separate belt is to be used, it is customary first to stitch the bottom of the blouse to the top of the skirt on the wrong side, then to apply a top stitch on the right side of the goods over the first stitch. Usually a finishing stitch such as an overcast is supplied to the edge of the goods. To save material, the first stitch is applied quite near the end of the goods, and hence an insufficient margin is left for lowering the waist line. This has the further defect that regardless of whether the waist line is lowered the very slightest amount possible or whether it is raised any suitable amount, it is necessary to remove the three stitches before mentioned. This is objectionable from the standpoint of the retailer because the one-piece dress or uniform sells for a comparatively low price and the cost of changing the waist line adds a very large percentage to the cost of the dress. It is objectionable from the standpoint of the consumer for the reason that it involves a substantial amount of work to remove three stitchings before making the alterations, and even so, only a negligible amount of lengthening is usually possible.

Similar objections apply to the customary one-piece dress or uniform having a set-in belt. Heretofore this belt has been made in two pieces, namely, a front and a back. The back part of the belt is stitched at its top to the bottom of the blouse and at its bottom to the top of the skirt. Then the outer half of the belt is stitched to the blouse and skirt over the two first stitchings. This has the disadvantage that it is not possible to lengthen the waist line. Also, if it is desired to shorten the waist line, it is necessary to rip the two seams which hold the top of the front and back halves of the belt to the bottom of the blouse.

The demand for an accurately fitting waist line is so great that the retailer frequently requires the dress manufacturer to furnish such dresses in sizes which vary by one-half size.

An object of the invention is to overcome the above objections, and provide a one-piece dress or uniform having a waist line which can be either raised or lowered with a comparatively

small amount of work, whereby the waist line may be readily raised or lowered, more in certain places than others if desired, and whereby it is unnecessary to supply the retailer with dresses in one-half size.

For further details of the invention, reference may be made to the drawing wherein

Fig. 1 is a view in elevation of a one-piece dress or uniform having a set-in belt according to the present invention.

Fig. 2 is an enlarged sectional view on line 2—2 of Fig. 1 looking in the direction of the arrows, with parts broken away, and showing the normal position of the stitching of the top of the belt and the bottom of the blouse as the goods are offered for sale by the retailer.

Fig. 3 is a view corresponding to Fig. 2 with the waist line raised, after removing the stitching at the top of the belt in Fig. 2 and restitching as indicated in Fig. 3.

Fig. 4 is a view corresponding to Fig. 2 with the waist line lowered after removing the stitching in Fig. 2 and restitching as indicated in this figure.

Fig. 5 is a front elevational view, with part of the skirt broken away, of the invention as applied to a one-piece dress or uniform having a separate belt.

Fig. 6 is an enlarged sectional view, with parts broken away on a line parallel to line 8—8 in Fig. 5 through one of the belt loops.

Fig. 7 is a sectional view corresponding to Fig. 6, with the floating loop in a raised position for a waist line higher than the seam shown. This loop can similarly be lowered to position the belt below the position shown in Fig. 6.

Fig. 8 is an enlarged sectional view with parts broken away on line 8—8 of Fig. 5 looking in the direction of the arrows, and illustrating the manner of securing the blouse and skirt at the waist line as it is sold to the customer.

Fig. 9 is a sectional view corresponding to Fig. 8 with the skirt sewed to the blouse by a second seam to raise the waist line.

Fig. 10 is a sectional view corresponding to Fig. 8 with a second seam applied between the first stitching and the end of the goods to lower the waist line.

Fig. 11 is a sectional view corresponding to Fig. 10 illustrating the relative position of the parts after the first stitching has been removed.

Referring in detail to the drawing, the dress 1 is here illustrated as a one-piece uniform having an open front which may be secured closed by buttons or the like 2. The dress 1 is provided with

a belt 3 which is different from prior constructions as illustrated in Figs. 2, 3 and 4, in that the belt is formed by taking a piece of goods which is the length of the belt but double the width thereof and folding it lengthwise in the middle whereby this fold indicated at 4 is to form the top of the belt. The top of the skirt 5 is stitched between the front belt portion 6 and the back belt portion 7 of the belt 3 as indicated at 8 with the back 7 of the belt 3 facing the right side of the blouse 9. The top of the belt 3 adjacent the fold 4 is stitched to the blouse 9 as indicated at 10, while leaving a substantial length, such as an inch and a half of the bottom of the blouse 9 as indicated at 9' projecting beyond the stitching 10 to make it possible to lower the waist line.

Fig. 2 illustrates the condition of the goods as sold to the customer, the stitching 10 being permanent enough to satisfactorily hold the blouse 9 to the skirt 3. It is only necessary to remove this single stitching 10 if it is desired to either raise or lower the waist line. In this case, the stitching 10 is first removed and then the belt 3 may be shifted up as indicated in Fig. 3 to raise the waist line, the top of the belt 3 being restitched to the blouse 9 as indicated at 11, or after stitching 10 is removed, the blouse 9 and skirt 5 are relatively separated and the top of the belt 3 is restitched lower on the blouse 9 as indicated at 12.

Figs. 5 to 11 illustrate the invention as applied to a one-piece dress or uniform 13 having a detachable belt 14 held at the waist line by a suitable number of loops 15, 16. Figs. 5, 6 and 8 illustrate the arrangement of the parts as the dress is sold to the customer, Fig. 7 illustrating how the belt 14 may be shifted up if the waist line is higher than the seam 17, while Figs. 9, 10 and 11 illustrate simple alterations which may be made by the retailer or the customer to either raise or lower the waist line.

Referring to Figs. 5 to 11, the bottom of the blouse 18 is secured to the top of the skirt 19 by the single stitching 17, this stitch being made on the wrong side of the goods, the stitching 17 being applied at such a point as to leave an extended end 18' of the blouse 18, and an extended margin or end 19' of the skirt both projecting about the same length and a substantial distance such as an inch and one-half beyond the stitching 17 in order to make it possible to lower the waist line, i. e., the line of stitching 17. As the stitching 17 is made on the wrong side of the goods, it will be apparent that the right side of the goods for the extensions 18' and 19' are in face-to-face relation. The loop 15 is flexible and may be of the same cloth as the material of the dress 13. The loop 15 is a floating loop, its ends 20 and 21 being brought together behind the horizontal center of belt 14 and held with the stitching 17. If the user does not care to go to the trouble of shifting the seam 17 up or down, a certain adjustment of the waist line may be obtained by sliding the belt 14 upwardly as shown in Fig. 7, the bottom of the belt then approaching the seam 17 as indicated. Similarly the belt 14 may be shifted downwardly to lower the waist line, to bring the top of the belt 14 adjacent the seam 17, and the parts would then appear somewhat as indicated in Fig. 7 if it is turned upside down.

If it is desired to raise or lower the waist line which is substantially the line of seam 17, this may be done as illustrated in Figs. 8 to 11, which for convenience omit the loop 15. Fig. 8 as above stated illustrates the normal position of the seam

17 when the dress is sold to the customer. If it is desired to raise the position of seam 17 to raise the waist line, this may be readily done as indicated in Fig. 9 by first leaving the stitching 17 on the goods to hold the blouse 18 and the skirt 19 in their proper relative positions, and by applying a stitching 22 above the stitching 17. Thereafter, the extensions 18' and 19', and the stitching 17 if desired may be cut off.

If it is desired to lower the waist line position of stitching 17, as indicated in Figs. 10 and 11, a second stitching 23 may be applied between the stitching 17 and the end of the extensions 18' and 19', while the stitching 17 remains in place to hold the blouse 18 and skirt 19 in their proper relative positions. Thereafter, the stitching 17 is removed and the stitching 23 then serves as the waist line stitching to hold the blouse 18 and skirt 19 together.

In case of waist line alteration as indicated in Figs. 3 and 4, and also in Figs. 9, 10 and 11, it will be apparent that the waist line may be raised or lowered more in the front or in the back as desired. The provision of the extension 9' in Fig. 2 and the provision of the extensions 18' and 19' in Fig. 8 make it possible to lower the waist line, and it may be raised or lowered with small inconvenience as the stitching 10 in Fig. 2 and the stitching 17 in Fig. 8 each comprise only a single stitching which need to be removed. In fact, the stitching 17' does not have to be removed if the waist line is raised as indicated in Fig. 9, while it does need to be removed if the waist line is lowered as indicated in Fig. 11.

It will be apparent that various modifications may be made in the invention without departing from the spirit of the following claims.

I claim:

40 1. A dress comprising a blouse and a lower garment, i. e., skirt or slacks, said lower garment terminating at its top in a one-piece set-in belt with the back of the belt in a fold behind the front of the belt, a first stitching securing the 45 top of said lower garment between the margins of said fold, a second stitching, namely, only a single stitching, securing the bottom of said blouse and said lower garment, said second stitching securing the top of said belt with the margin 50 of the bottom of said blouse extending below said second stitching on the wrong side of said blouse and lower garment a distance sufficient to permit the waist line to be lowered a substantial distance, whereby the waist line may be raised or 55 lowered and restitched on removal of said second stitching.

2. A dress comprising a blouse and a lower garment, i. e., skirt or slacks, only a single stitching securing the bottom of said blouse and the top 60 of said lower garment at the waist line to form a one-piece dress, and the margin of the bottom of said blouse extending below said stitching on the wrong side of said blouse and lower garment a distance sufficient to permit the waist line to be lowered a substantial distance, said lower garment terminating at its top in a one-piece set-in belt with the back of the belt in a fold behind the front of the belt, stitching securing the top 65 of said lower garment between the margins of said fold, and said single stitching securing the top of said belt above the bottom of said blouse with said belt and said blouse overlapped with the back of said belt facing the right side of said blouse, whereby the waist line may be raised or 70 lowered.

75

lowered and restitched on removal of said single stitching.

3. A dress comprising a blouse and a lower garment, i. e., skirt or slacks, only a single stitching securing the bottom of said blouse and the top of said lower garment at the waist line to form a one-piece dress, and the margin of the bottom of said blouse extending below said stitching on the wrong side of said blouse and lower garment a distance sufficient to permit the waist line to be lowered a substantial distance, said single stitching permitting the waist line to be lowered with the removal of only one waist line stitching, namely said stitching securing the bottom of said blouse and the top of said lower garment, and a belt loop having its ends secured in said single stitching and being flexible to permit the belt position of said loop to be raised or lowered with respect to said single stitching.

4. A dress comprising a blouse and a lower 20 garment, i. e., skirt or slacks, said lower garment

terminating at its top in a one-piece set-in belt with the back of the belt in a fold behind the front of the belt, a first stitching securing the top of said lower garment between the margins of said fold, a second stitching, namely, only a single stitching, securing the bottom of said blouse and said lower garment, said second stitching securing the top of said belt with the margin of the bottom of said blouse extending below said second stitching on the wrong side of said blouse and lower garment a distance sufficient to permit the waist line to be lowered a substantial distance, whereby the waist line may be raised or lowered and restricted on removal of said second stitching, and a belt loop having its ends secured in said second stitching and being flexible to permit the belt position of said loop to be raised or lowered with respect to said second stitching.

HENRY J. PEARL.
